UNITED STATES PATENT OFFICE.

JOHN L. RIVELY, OF PRIMOS, PENNSYLVANIA.

ROCKING-HORSE.

SPECIFICATION forming part of Letters Patent No. 775,192, dated November 15, 1904.

Application filed December 11, 1903. Serial No. 184,721. (No model.)

To all whom it may concern:

Be it known that I, JOHN L. RIVELY, a citizen of the United States, residing at Primos, Delaware county, and State of Pennsylvania, 55 have invented a certain new and amusing Improvement in Rocking-Horses, of which the following is a specification.

My invention relates to an improvement in rocking-horses, and has for its object to provide a rocking-horse which shall have the usual rocking motion, which motion will at the same time cause the horse and rider to travel forward.

With this end in view this invention consists in the details of construction and combination of elements hereinafter set forth and then specifically designated by the claim.

In order that those skilled in the art to which this invention appertains may understand how 20 to make and use the same, the construction and operation will now be described in detail, referring to the accompanying drawings, forming a part of this specification, in which—

Figure 1 represents a side elevation of my 25 invention; Fig. 2, a rear view of the same. Figs. 3, 4, and 5 are diagrams illustrating the different positions of the rocker to accomplish the forward movement.

A represents the body of the horse.

30 B represents two rockers arranged upon each side of the horse and pivoted to the same at the point C, the arms D extending forward from the rockers and connecting said rockers with the pivotal point. To the forward arm D is connected a spring E. The other end of this spring is connected to the body of the horse. F is a second pair of rockers arranged upon each side, but just within the forward rockers.

40 G represents arms extending upward from the rockers and meeting at the point H, where they are pivoted to the body of the horse at the rear part thereof.

I is a spring one end of which is connected 45 to the forward arm G and the other end to the body.

Slots are formed in the body of the horse to allow the arms D and G to protrude up 50 within the body, and these slots are cut so as 55 to allow the rockers B and F a certain amount of movement upon the pivots C and H.

It is obvious that when the rockers are out of contact with the arms the springs E and I will pull the rockers forward to the limit of their movement in one direction.

55 In the diagram shown in Figs. 3, 4, and 5 the letter J represents the stop limiting the movement of the forward rocker in one direction, and J' represents the stop limiting the movement of the forward rocker in the opposite direction. K represents the stop limiting the movement of the rear rocker in the forward direction, and K' represents the stop limiting the movement of the rear rocker in the opposite direction. When the horse is 60 rocked forward upon the forward rocker, as illustrated in Fig. 3, the weight of the body and the rider will cause the rear arm D of the forward rocker to come in contact with the stop J'. This will expand the spring E 65 and also cause the rear rocker F to be raised from contact with the ground. The spring I then acting upon this rear rocker will pull the same forward until the forward arm G of that rocker comes in contact with the stop 70 K. Then upon the return movement, or when the horse is rocked upon the rear rocker in the position shown in Fig. 4, the weight of the body of the horse and the rider will cause the forward arm G of the rear rocker 75 to remain in contact with the stop K, and this will cause the forward rocker B to be raised from out of contact with the ground, which will allow the spring E to act and pull such rocker forward in contact with the stop J, 80 and upon the return motion or in rocking forward the center of gravity will change and the momentum of the body of the horse and the rider will carry the body of the horse, and thereby the rider, forward before the front 85 rockers B come in contact with the ground, and this will bring the rear arm G of the rear rocker in contact with the stop K' and will at the same time expand the spring I. Then 90 as the motion forward continues the weight of the rider will cause the rocker B to come in contact with the stop J' and raise the rockers F from out of contact with the ground and allow the spring I to act to bring the rockers F in contact with the stop K, when 95 the position of the rockers will be back to their original position, as shown and described

in connection with Fig. 3. It will be obvious that in this movement backward and forward upon the rockers the rocking-horse is moved forward a distance equal to the arc described 5 by the movement of the rockers upon the pivots C and H.

Of course it is obvious that a forward movement could be accomplished by simply pivoting the forward rockers and making the 10 rear rockers stationary with the body of the horse; but by pivoting both sets of rockers I obtain a double movement forward upon each 15 backward-and-forward rocking movement of the horse, which will cause the same to travel always as fast as if only one set of rockers were pivoted.

The advantage of my invention is that it will give a great amount of amusement to children using this rocking-horse, as they obtain 20 a forward movement as well as a rocking movement at the same time, which will indicate the galloping of a horse.

My apparatus being simple and composed of few parts is not liable to become out of 25 order or damaged and will enable the apparatus to be manufactured at a comparatively low cost.

Of course I do not wish to be limited to the

exact construction here shown, as slight modifications could be made without departing 30 from the spirit of my invention.

Having thus fully described my invention, what I claim is—

In a rocking-horse, a body, two sets of rockers, one set arranged at the forward part of 35 the body and the other set arranged in the rear, arms extending up from the forward rockers to a meeting-point, said arms being pivoted to the forward end of the body at this meeting-point, arms extending upward 40 from the rear rockers to a meeting-point and being pivoted to the rear of the body at this meeting-point, stops arranged upon the body to abut against these arms and limit the motion of the rockers upon their pivots, springs, 45 one end of which is secured to the forward arms of each pair of rockers and the other end to the body of the horse, as and for the purpose set forth.

In testimony whereof I have hereunto affixed 50 my signature in the presence of two subscribing witnesses.

JOHN L. RIVELY.
